CLAIM

I claim the ornamental design for a barbecue grill cover, as shown and described.

DESCRIPTION

FIG. 1 is a top plan view of a barbecue grill cover showing my new design;

FIG. 2 is a side view thereof; and,

FIG. 3 is a side view of the leading edge thereof.

FIGS. 1 and 2 are shown broken away and represent indeterminate length.

1 Claim, 2 Drawing Sheets

FIG. 1

FIG. 3
